PREFABRICATED PANEL AND WARMING
MEANS THEREFOR

Max C. Richardson, Portland, Oreg.

Application September 17, 1946, Serial No. 697,410

3 Claims. (Cl. 219—19)

1

This invention relates generally to building constructions and particularly to a board for use in such constructions.

The main object of this invention is to provide a simple and efficient form of panel whereby heat may be easily and safely delivered to a space through the floor, walls or ceiling thereof, or by employing same as a screen or additional floor covering.

The second object is to produce a board which will operate at a temperature so low that it may be operated continuously without any danger of charring or disintegrating the wooden base upon which it is formed.

The third object is to so construct the board that its dimensions will adapt it to use in ordinary building constructions by keeping these dimensions in multiple of standard studding and joist spacings.

The fourth object is to construct a board of wood in a manner to fill all of the voids therein to prevent an undesirable accumulation of heat at any specific point.

The fifth object is to so construct the board that it may be easily assembled with other units by means of a special connector which I have provided.

The sixth object is to so construct the unit that current may be supplied thereto through either side of the board by merely removing a cover plate therefrom.

The seventh object is to so construct the board and arrange the warming elements therein that the entire surface of the board may be uniformly warmed at any one of three predetermined rates.

I accomplish these and other objects in the manner set forth in the following specification as illustrated in the accompanying drawings, in which:

Fig. 1 is a plan of a representative form of the board.

Fig. 2 is a fragmentary perspective view of one corner of the board showing a form of terminal in which three connecting pins project into a recess, the upper and lower sides of which are metal plates.

Fig. 3 is a fragmentary perspective view showing a form of filler plug to fill and insulate the terminal recess when no connection is made to this side of the board.

Fig. 4 is a perspective view of the connecting plug used with the construction shown in Fig. 2.

Fig. 5 is a sectional view showing the corner portions of two panels or boards connected by means of the block shown in Fig. 4.

2

Fig. 6 is a fragmentary perspective view showing the manner of connecting the board to a power line.

Fig. 7 is a perspective view showing several panels mounted on the under side of joists.

Fig. 8 is a perspective view of one or more panels and the method of connecting them for portable or temporary use.

Similar numbers of reference refer to the same or similar parts throughout the several views.

Referring in detail to the drawing, there is shown by way of example a rectangular board 13, which in this case consists of a number of plies 11, 12, 13 and 14, preferably of wood, which are firmly bonded together by means of a waterproof glue after the necessary warming elements have been installed.

Between the plies 12 and 13 are disposed the resistance elements 15 and 16 which are connected to the lead wires 17, 18, and 19, as illustrated, in order that they may be operated independently, in series or in multiple.

The lead wires 17, 18, and 19 extend across one end of the board and terminate at the connecting pins 20. As shown in Fig. 2 and Fig. 5, the terminal pins are firmly spaced and supported by the fiber block 24. The precise manner of connecting the resistance elements 15 and 16 to the lead wires 17, 18, and 19 is so well understood that it need not be elaborated upon here.

It is imperative that when the elements 15 and 16 are put into place between plies 12 and 13 that they be hermetically sealed between the plies of wood and that all voids be eliminated since it follows that unless the heat can be conducted away from the elements it could accumulate and the temperature arise to an objectionable degree.

The resistance or heating element comprises two separate resistance wires 15 and 16, one of approximately 53 feet of 25 B. & S. gage Nichrome and the other of approximately 53 feet of 22 B. & S. gage Nichrome wire. The resistance wires are placed in such a way between the two plywood panels as to be each approximately uniformly distributed over the panel and each approximately uniformly spaced from the other. One end of each wire is attached to lead wire 19 and the other end of one of the resistance wires is attached to lead wire 17, while the other end of the other resistance wire is attached to lead wire 18.

Assuming an electrical supply line of 118 volts, when the lead wires are so connected to the supply line that the 22 gage wire is energized, the heat released is a total of approximately 250

watts. When the 25 gage wire is energized, the heat released by this wire is approximately 125 watts or when both wires are energized the heat released is approximately 375 watts. Since the panel is four feet square, this gives an approximate heat release of 27, 54, or 81 British thermal units per square foot, which not only covers the entire range of heat release found desirable in the many uses of panel heating of space, but also keeps the panel temperature low to eliminate all fire hazards.

It is within the concept of my invention to produce these boards as units which may be used separately or in any desired combination to supply heat at some particular place on the floor, wall, or ceiling, or over an extended area if desired. It is also within the concept of my invention that these boards may be used as temporary floor panels or wall screens or that they may be permanently installed as panel heating units of the floor, wall, or ceiling structure.

For example, these boards have been found to have great utility in overcoming objectionable cold floor conditions in an office where one or more boards may be placed as a temporary floor under an office desk and chair. The same great utility has been found in the home where, for instance, one or more boards are laid as a temporary floor under a chair used by an older person or an invalid. When thus used as a temporary floor panel, the board may be energized and controlled with a portable electric cord as shown in Fig. 8 where 50 is an ordinary 2-prong electric cord attachment plug, 51 is a length of ordinary 2-wire electric appliance cord, 52 is a usual type of in-the-cord 3-heat switch, 53 is a length of 3-wire electric appliance cord, and 54 is a specially made 3-point plug for insertion into one terminal recess of board 10 and connecting the 3 wires of cord 53 to the terminal pins 20 of lead wires 17, 18, 19 of board 10. It is desirable to arrange plug 54 so that it will only be inserted into the terminal recess of board 10 in such a way as to give validity to the heat markings on switch 52.

When a single board unit is to be used, the terminal recess not used for energizing the board will be filled and insulated by the insulating plug 22 shown in Fig. 3 and Fig. 8. When more than one board is to be used to make up a heating panel, they may be grouped for one attachment to the source of power by electrically connecting adjacent boards with the through plug 62 as shown in Figs. 4, 5, 7 and 8. In this case insulating plug 22 is used to fill the unused terminal recess of the final board attached to the panel as shown in Fig. 8.

Fig. 7 is a perspective drawing showing how my boards may be permanently installed as a ceiling panel for panel-heating a room from the ceiling. Referring to Fig. 1, 10 illustrates my board 10 as it is constructed in a four foot by four foot size. In this size, it can be readily attached to a building frame with stud and joist spacing of either sixteen inches or twenty-four inches center to center spacing. In Fig. 1, 71, 72, and 73 are shown either as pre-drilled nailing or screw holes, or they can be factory markings on the board for drilling or nailing in the field. In Fig. 7 the ceiling joists are represented as of twenty four in. center to center spacing, and in this case the board would be attached to the ceiling joists at positions 71 and 72 of Fig. 1. If the ceiling joists were spaced

sixteen inches center to center, attaching positions 71 and 73 would be used.

When a permanent installation is made as in Fig. 7, no flexible attachment cord may be used and I have therefore provided a special conduit box cover plate 21 to take the place of one of the cover plates 25. Also for this use, as shown in Fig. 6, I have provided a system of insulating barriers to slide over terminal pins 10 20 and have provided each of the pins 20 with a single connection 31 for attaching to the electric service wires.

Referring again to Fig. 7, it is seen that when my board is permanently installed, the electrical connection is concealed at the back of the board and that the room side of the board is smooth and may be finished in any way desired to match the room decorative scheme. For most efficient use of heat in the room, the space between the joists on the back side of the panel may be filled to any desired depth with any of the usual forms of heat insulating materials.

I am aware that panel heat of itself is not new and that numerous other devices such as heat pads and other contrivances have been constructed in the past. It is, therefore, not my intention to cover such devices broadly, but I do intend to cover such forms and modifications thereof as fall fairly within the appendant claims.

I claim:

1. A pre-fabricated plyboard comprising a pair of plies of substantially rigid electrically insulating material secured together by a layer of electrically insulating adhesive material and having a wire resistance element embedded in said layer, said wire being of relatively small cross sectional area and of relatively great length and being extensively laid over the inner surfaces of said plies in a pre-determined pattern whereby when said wire is electrically energized it will heat said plyboard substantially uniformly over its area and whereby said wire will be substantially spaced from pre-determined points of perforation of said plyboard, said plyboard being marked on one face with indicia corresponding to a pre-determined standard of building framing whereby at said indicated points on said face it will be safe to perforate said plyboard to secure said plyboard to the supporting structure of a building, one of said indicia being within the surface area of said plyboard covered by said resistance element.

2. A plyboard adapted for radiant heating comprising a pair of electrically insulating plies of substantially rigid electrically insulating material secured together by a layer of electrically insulating adhesive material and marked on one surface with positions where said plyboard may be perforated for securing said plyboard to a building structure of pre-determined form, in combination with a bare wire resistance element of small cross sectional area and relatively great length embedded in said layer and extensively laid whereby when said element is electrically energized said wire will supply heat substantially uniformly over the surface of said plyboard but will be safely spaced from said positions of perforation.

3. A prefabricated electric heating board comprising upper and lower plies, a layer of electrically insulating adhesive material, an electric resistance wire, and a pair of relatively low resistance conductors, one end of said wire being connected to one of said conductors and the

other end of said wire being connected to the other of said conductors, said wire and said conductors being embedded in said material between said plies, one end of each of said conductors extending from between said plies near one edge of said board and the other end of each of said conductors extending from between said plies near another edge of said board, whereby when multiples of said boards are abutted edge to edge to form a heating panel the ends of said conductors extending from between the plies of adjacent edges of said boards are juxtaposed for ready series connection of the conductors of adjacent boards thereby to connect said wires of said adjacent boards in multiple.

MAX C. RICHARDSON.
